[57] CLAIM

The ornamental design for a transformer base plastic door, as shown and described.

DESCRIPTION

FIG. 1 is a front elevational view of a transformer base plastic door showing my new design;
FIG. 2 is a back elevational view thereof;
FIG. 3 is a side elevational view thereof, the view from the opposite side being a mirror image;
FIG. 4 is a top plan view of FIG. 2; and,
FIG. 5 is a bottom view of FIG. 1.
